UNITED STATES PATENT OFFICE

168,193

FIGURINE

Hans Maassen Schümann, Philadelphia, Pa.;
Josephine Mason Petts executrix of said Hans
Maassen Schümann, deceased

Application January 8, 1952, Serial No. 17,966

Term of patent 14 years

(Cl. D29—23)

To all whom it may concern:

Be it known that I, Hans Maassen Schumann, a citizen of the United States, residing in Philadelphia, county of Philadelphia, State of Pennsylvania; have invented a new, original, and ornamental Design for a Figurine, of which the following is a specification, reference being had to the accompanying drawing, forming a part hereof.

Fig. 1 is a side elevational view of a figurine showing my new design;

Fig. 2 is a side elevational view taken from the opposite side thereof;

Fig. 3 is a front elevational view thereof; and

Fig. 4 is a rear elevational view thereof.

I claim:

The ornamental design for a figurine, as shown.

HANS MAASSEN SCHUMANN.
